SAND PACKER FOR POTTERY

James A. Bower, Chester, W. Va., assignor to The
Taylor, Smith & Taylor Company, East Liver-
pool, Ohio, a corporation of West Virginia

Application June 10, 1943, Serial No. 490,324

8 Claims. (Cl. 259—2)

This invention relates to an apparatus for use in the packing of sand about pottery arranged in stacks to be placed in firing kilns.

It is often desirable in the firing of pottery to support the articles at every point of the under surface of their rims so as to entirely eliminate sagging and warping. For this purpose it is usual to pack sand between the articles arranged in stacks so that they are nested in the sand. The process of manually packing the sand about the articles is both tedious and time consuming, and quite often results in the production of defective ware due to the absence of supporting sand at various points between the rims of adjacent articles, or because of the repeated handling of the articles while in their fragile condition prior to firing.

A primary object of the present invention resides in the provision of an apparatus for automatically packing sand in the annular crevices between stacked articles, so as to avoid unnecessary handling of the articles, as well as to provide a uniform and thorough packing of the sand.

More specifically, it is an object of the invention to provide a simplified mechanism by which sand is automatically deposited about stacks of articles, the stacks vibrated to cause the sand to crowd into and pack the series of spaces between the stacked plates or the like, and surplus sand automatically discharged into a receptacle from which it is elevated and deposited into a bin from which it is subsequently discharged and deposited about succeeding stacks of ware placed in the apparatus.

A further object of the invention resides in the provision of a sand packing apparatus of relatively few operating parts so as to not only simplify its construction but also to reduce to a minimum both the cost of operation and time lost due to shut-downs because of disorganization of the moving parts.

Other objects and advantages of the invention will be apparent from the following description when taken in connection with the accompanying drawings, in which,

Figure 1 is a front elevational view of the apparatus.

Figure 2 is a side elevational view thereof.

Figure 3 is a plan view of the apparatus with the storage bin removed.

Figure 4 is a plan view, on an enlarged scale, of a rotatable series of containers which receive the stacks or bungs of partly formed ware.

Figure 5 is a vertical sectional view through the series of containers and related parts, and

Figure 6 is an enlarged fragmentary sectional view showing the vibratory mounting for the spider which supports the containers.

Referring to the drawings in greater detail, the numeral 1 indicates a floor or other base from which extend a plurality of vertical standards 2 connected at their upper ends by horizontal bars 3 and 4 to form the main framework of the apparatus.

Mounted in the upper portion of the frame of the apparatus, as indicated in Figures 1 and 2, is a storage and dispensing bin 5 adapted to receive sand through its upper end, and provided with a discharge pipe or nozzle 6 at its lower end. Mounted at one side of the bin 5 and extending vertically of the apparatus is a bucket conveyer 7 provided with an endless series of buckets 8. This conveyer may be operated through the medium of an electric motor 9 and reduction gearing 10, mounted on a platform 11 adjacent the top of the apparatus.

The lower end of the bucket conveyer 7 is located in a receptacle or bin 12 disposed at the bottom of the apparatus just below the floor 1 and adapted to receive surplus sand from the containers on the revolvable table, as will appear hereinafter. The upper end of the conveyer extends to a plane somewhat above the top of the storage bin 5, and the adjacent edge of the top of the bin is provided with a guide strip 13 to direct the sand into the bin as it is projected from the buckets 8 after the latter travel over the upper roller of the conveyer.

Rotatably mounted directly below the nozzle 6

35 of the storage bin 5 is a table or spider on which are supported four buckets or containers 14, although it is to be understood that the number of containers may be varied as desired. This part of the apparatus includes a vertical shaft 15 mounted in bearings 16 and 17 and provided with a boss 18 secured on its upper end. Secured to the upper face of the boss 18, as by bolts 19, is a plate 20. Interposed between the elements 18 and 20 is a rubber pad 21 of sufficient thickness to permit the desired vibration of the containers 14 and the ware carried thereby, as will appear hereinafter. A sleeve 19' (Fig. 6) having an inner diameter slightly greater than the exterior diameter of the bolts to allow sufficient

40 play therein, surrounds each of the bolts 19 and serves as a spacer to prevent undue compression of the rubber pad 21.

Extending across the top of plate 20 and firmly secured thereto is a spider comprising a pair of 45 right-angularly arranged bars 22 constituting a

50

carrier for the containers 14. Adjacent their outer ends these bars are provided with transversely extending bars 23 thereby forming secondary spiders upon which the bungs or stacks of ware may be supported. As clearly indicated in Figure 5, the spiders are surrounded by the walls of the containers or buckets 14, and the walls of these containers are provided with diametrically disposed pockets or bulges 24 to provide clearance for the hands of the operator in depositing and removing the stacks of ware from the containers.

The containers 14 are provided with downwardly tapered or funnel-shaped bottoms 26, in each of which is formed a discharge opening 27 to permit the escape of surplus sand at the proper time. Disposed in a plane immediately below the bottom of the containers 14 is an arcuate valve plate 28 extending through an arc of somewhat more than 90° and serving as a closure for a container at the charging station and at the next station thereafter. When a container passes beyond the plate 28 the surplus sand is free to leave the particular container, and an inclined plate or chute 29 is provided to direct such sand into the bin 12. Shaft 15, which supports the rotating table, extends through an opening in chute 29 and in order to protect the shaft and related parts from the sand descending in the chute a sleeve 30 is extended upwardly from the chute to which it is attached and encircles the shaft.

In order to vibrate the containers 14 and the stacks of ware therein so as to cause the sand to pack into the crevices between the plates or the like, an electric vibrator is provided in a housing 31. The vibrator may be of any well known commercial type, and is mounted on a plate 32 secured on the adjacent edges of the four containers 14. The conducting wires 33 for the vibrator preferably extend downwardly through the sleeve 30 and the opening in chute 29, and are then connected with a pair of rings 34 associated with brushes 35. This circuit is preferably controlled by a time switch which, after being closed by the operator will remain closed for about four seconds.

The complete operation of the sand packing apparatus will now be described.

Assuming the bin 12 is charged with sand and the bucket conveyer 7 is being driven by the motor 9, a bung or stack of plates or other pottery to be fired is placed in the container 14 at station A, the ware resting on the spider in the container. The table is now manually rotated 90°, as by a handle 25, to bring the container to station B where it receives a charge of sand and is then vibrated for a four second interval by the closing of the vibrator switch. The container is then moved through 90° to bring it to station C where it is again vibrated for the period mentioned. The table is again rotated to bring the container to station D which is spaced beyond the end of the valve plate 28. At this station the surplus sand is automatically discharged from the container and the completely and uniformly packed stack of plates is removed by the operator, and is ready to be transferred to the firing kiln.

After the operator removes the sanded stack of ware at station D and before the operator at station A introduces a fresh stack in the container at that station, he closes the vibrator switch so as to cause the vibration of stacks of ware at stations B and C. It will thus be apparent that no stack of ware is vibrated until completely surrounded by a charge of sand, and that no sanded stack is vibrated after the surplus sand

has been drained from its container. Hence there is no possibility of the ware of unsanded stacks being shaken out of vertical alignment, nor of the sand being shaken loose from completely sanded stacks.

In the course of charging sand into the several containers, it will be noted that the discharge of sand from the nozzle 6 to each container is automatically cut off when the sand piles up to close the lower end of the nozzle, and that it automatically begins to flow into the succeeding container as soon as the filled container is moved to station C. The arcuate valve plate 28 serves to close the lower ends of the containers at stations B and C and during their travel between these stations, and automatically opens the lower ends of the containers when they reach station D; the surplus sand traveling down chute 29 to the lower bin 12, from whence it may be raised to the dispensing bin 5 by the elevator 7.

The foregoing operations are continued so long as the apparatus remains in operation; it being understood of course that new sand must be added from time to time to take the place of sand deposited in the crevices of the stacks.

It will be understood of course that by extending the valve plate 28 to station D, each charged container could be given three periods of vibration. In such event an operator would be employed only at station A, and he would load and unload the containers at that station.

From the foregoing description taken in connection with the accompanying drawings it will be apparent to those skilled in the art that I have devised a simple and inexpensive apparatus which is strong, durable and inexpensive in operation, and yet provides a mechanical means whereby sand is expeditiously and thoroughly packed in the annular spaces between a stack of plates so as to provide a uniform support throughout the under surface of the rims of the individual articles.

In accordance with the patent statutes I have described what I now believe to be the preferred construction of the apparatus, but inasmuch as various changes may be made in the construction without departing from the spirit of the invention, it is intended that all such changes be included within the scope of the appended claims.

What I claim is:

1. Apparatus for packing sand about stacks of pottery, comprising a vertically disposed shaft, a resilient member disposed on the upper end of the shaft, a horizontally arranged carrier member having its central portion clamped on the resilient member, a plurality of containers supported on the carrier, means for charging sand into the containers, and means for vibrating the carrier.

2. Apparatus for packing sand about stacks of pottery, comprising a vertically disposed shaft, a rubber pad disposed on the upper end of the shaft, a pair of crossed bars constituting a carrier and having their mid-portions supported by the rubber pad, a plurality of containers supported on the carrier, means for charging sand into the containers, and means for vibrating the carrier.

3. Apparatus for packing sand about stacks of pottery, comprising a rotatable table, a plurality of open-ended containers carried thereby and adapted to receive stacks of pottery, means for closing and opening the lower ends of said containers during the rotation of the table, means for charging sand into the containers, and means for vibrating the containers.

4. Apparatus for packing sand about stacks of pottery, comprising a rotatable table, a plurality of open-ended containers carried thereby and adapted to receive stacks of pottery, an arcuate plate spaced slightly below the path of travel of the containers and adapted to close the lower ends of the containers during a portion of their travel, and means for charging sand into the containers.

5. Apparatus for packing sand about stacks of pottery, comprising a rotatable table, a plurality of open-ended containers carried thereby and adapted to receive stacks of pottery, an arcuate plate spaced slightly below the path of travel of the containers and adapted to close the lower ends of the containers during a portion of their travel, a chute disposed below the containers and adapted to receive surplus sand therefrom, a bin for receiving sand from the chute, means for charging sand into the containers, means for raising sand from the bin to the charging means, and means for vibrating the containers.

6. Apparatus for packing sand about stacks of pottery, comprising a spider adapted to rotate about a vertical axis, secondary spiders formed adjacent the ends of the first-mentioned spider, containers in which the secondary spiders are located, said containers adapted to receive stacks of pottery, means for directing sand into the

containers, and means for vibrating the containers.

7. Apparatus for packing sand about stacks of pottery, comprising a rotatable table, a plurality of containers carried thereby and adapted to receive stacks of pottery, said containers having openings in the top and bottom, an open support in each of the containers upon which the stacks of pottery rest, means for charging sand into the containers, means for closing and opening the lower ends of the containers, means for vibrating the containers, a bin, and means for directing sand discharged from the containers to said bin.

8. Apparatus for packing sand about stacks of pottery, comprising an upper bin for sand, a rotatable table, a plurality of containers carried thereby and adapted to receive stacks of pottery, said containers having openings in the top and bottom, an open support in each of the containers upon which the stacks of pottery rest, means for charging sand into the containers from said upper bin, means for closing and opening the lower ends of the containers, means for vibrating the containers, a lower bin, means for directing sand discharged from the containers to said lower bin, and means for conveying the sand from the lower bin to the upper bin.
